T. H. COSTELLO,
MAP CABINET.
APPLICATION FILED FEB. 21, 1916.

Patented July 17, 1917.

UNITED STATES PATENT OFFICE.

THOMAS H. COSTELLO, OF CHICAGO, ILLINOIS.

MAP-CABINET.

1,233,316.

Specification of Letters Patent. Patented July 17, 1917.

Application filed February 21, 1916. Serial No. 79,710.

To all whom it may concern:

Be it known that I, THOMAS H. COSTELLO, a citizen of the United States, residing at the city of Chicago, in the county of Cook and State of Illinois, have invented certain new and useful Improvements in Map-Cabinets, of which the following is a specification.

My invention relates to cabinets in which a considerable number of maps may be placed on a suitable rack for convenient reference. It is the custom for school use and in other places where many maps are so used to mount them upon spring rollers similar to those used for window shades and to journal the rollers one above the other on upright racks. When so mounted the maps are readily drawn down or replaced as desired but in such movement, unless extreme care is used, the maps are drawn over each other, thereby wearing and defacing them. In some cases a forwardly inclined case or cornice has been used, whereby the different map rollers have been extended forwardly above the ones immediately below, thereby providing certain clearance. My improvement provides means by which a series of maps may be mounted within a closed cabinet on a movable rack which is there normally retained by gravity, but which may be automatically inclined to free the maps when the door of the cabinet is opened. A complete dust free cabinet of conventional design may thus be provided while, when wanted for use, the maps may be placed in convenient position therefor and in such relation to each other that the action of extending them or returning them to normal position will not deface or injure them.

The principles of my invention are illustrated in the drawings, in which—

Figure 1 shows a front view of my improved map cabinet with the door turned downwardly to disclose the interior;

Fig. 2 is a sectional view on the line 2—2 of Fig. 1, when the cabinet is closed.

Fig. 3 is a similar view showing the relation of the parts when the cabinet is opened;

Figs. 4 and 5 show one form of mutually engaging device in the positions corresponding to Figs. 2 and 3;

Figs. 6 and 7 show views of other forms of engaging devices.

Further describing my invention with reference to the drawings, in which like char-

acters of reference denote like parts throughout: 1 and 2 are the ends, 3 the back, and 4 the bottom board of a map cabinet. The top 5 is extended forwardly to form a cornice 6, 60 under which the door 7 may be received and secured by a catch 8 or other suitable means. The said door should be hinged at 9 to the baseboard 4, so that when opened it may turn downwardly and hang free in the position shown in Figs. 1 and 3. A map rack having the end pieces 10 and 11 has the lower part thereof pivoted adjacently to their forward edges at 12 to a positive abutment, this as shown, being the lower portion 70 of the cabinet. Such pivoting permits the map rack to be folded to a position in which it will be overbalanced within the case where it normally will be retained by gravity as shown in Fig. 2 or to be 75 turned forwardly in a slanting position as shown in Fig. 3, in which position it is held by means of the slotted links 14 the ends of which are attached respectively to the ends of the cabinet and of the map rack. The 80 two ends of the map rack are connected by a top piece 15 on the front edge of which is provided an upwardly projecting tongue or pin 16. On the inside of the door is provided a loop 17, so placed with reference 85 to the pin 16 that, when the door is raised from the position shown in Fig. 3, into contact with the map rack, the pin and loop will take respectively the positions shown in Fig. 5. When the door is further 90 closed, pushing the map rack into place, the pin and loop will be moved into engagement as shown in Fig. 4, and will so remain until it is desired to open the cabinet. As the door is opened the engagement 95 of the pin and loop causes the rack to be drawn forward on the pivot 12 until its weight overbalances. It will then fall to the operative position, where it is supported by the links 14. But at this point or before, the turning of the door on the hinge pivot 9 will cause the pin 16 to be withdrawn from the loop 17, thus freeing the door and permitting it to be completely opened to disclose the map rack.

An alternative form of engagement between the map rack and the door is illustrated in Fig. 6, in which a hook 20 may be attached to the face of the door in such position that it will engage the pins 21 on the 110 end pieces of the rack. Other forms of engagement and disengagement may be pro-

vided, but any equivalent construction in which the door and map rack are in differential relation and are engaged and disengaged by movement in arcs of different circles, is equally within the spirit and scope of my invention.

In Fig. 7 is shown a device which may be substituted for that shown in Figs. 4 and 5, a yielding latch 17' replacing the stationary 10 loop 17.

I claim:

1. In a map cabinet; a rigid abutment, a map rack hinged thereto, a door hinged to said abutment in differential relation to said 15 map rack, and mutually related devices on said door and on said rack adapted to engage with each other as the door is closed and to be disengaged during the door opening movement.

2. In a map cabinet; a case, a map rack hinged therein, a door hinged to said case in differential relation to said map rack, and mutually related devices on said door and on 25 said rack adapted to engage with each other as the door is closed and to be disengaged during the door opening movement.

3. In a map cabinet; a case, a map rack pivoted at its lower part within the case and forwardly inclinable therefrom, means for 30 limiting the forward inclination of said rack, a door hinged to the case and forwardly and downwardly turnable therefrom, and mutually related devices on said door and rack adapted for engagement with each other 35 when the door is closed and to be disengaged from each other during the opening movement of said door.

4. In a map cabinet; a case, a map rack pivoted at its lower part within the case and 40 forwardly inclinable therefrom, means for limiting the forward inclination of said rack, a door hinged to the case and forwardly and downwardly turnable therefrom, and relatively yielding and rigid devices on 45 said door and rack adapted for engagement when the door is closed and to be disengaged from each other during the opening movement of said door.

5. In a map cabinet; a case, a map rack 50 pivoted at its lower part within the case and forwardly inclinable therefrom, means for limiting the forward inclination of said rack, a door hinged to the case and forwardly and downwardly turnable therefrom, 55 a rigid striker plate on said rack and a hook

on the door said plate and hook being adapted for engagement when the door is closed and to be disengaged from each other during the opening movement of said door.

6. In a map cabinet, the combination of a 60 case, a map rack pivoted within the case adjacent to one side thereof, a door pivoted to the same side of said case out of axial alignment with the pivotal axis of the map rack whereby when simultaneously actuated said door and rack will have differential movement, and related means on the rack and door for engagement and disengagement by 65 said differential movement.

7. In a map cabinet; a case, a map rack 70 pivoted within the case adjacent to one side thereof, a door to close over said rack pivoted to the same side of the case, so that when simultaneously actuated they will move in arcs of different circles, and means carried 75 by said rack and door whereby they will be engaged by the closing and disengaged by the opening movement of the door.

8. In a map cabinet; the combination with a relatively stationary abutment, of a map 80 rack pivoted thereto at a point forwardly of and below the center of gravity of the map rack, whereby when closed said rack normally will be held in the closed position and means to connect the abutment and the map 85 rack to limit the forward inclination of the latter.

9. In a map cabinet; a case, a map rack pivoted therein to be forwardly inclinable 90 therefrom, said rack being hinged forwardly of and below its center of gravity to the said case, and means connected to the case and rack to limit the forward inclination of the latter.

10. In a map cabinet; a case, a map rack 95 pivoted within the case forwardly of and below the center of gravity of the said rack, whereby when closed the rack normally will be held in the closed position and means to connect the rack to the case and limit the forward inclination of the said rack. 100

In witness whereof, I have hereunto subscribed my name this 17th day of February, 1916, in the presence of two subscribing witnesses.

THOMAS H. COSTELLO.
